Primary Examiner — Kathleen L Jones*Assistant Examiner* — Cole Sanders Holman(74) *Attorney, Agent, or Firm* — Chiesa Shahinian & Giantomaso PC(57) **CLAIM**

The ornamental design for a keyboard, as shown and described.

DESCRIPTION

FIG. 1 is a front perspective view of a keyboard according to our design;

FIG. 2 is a top view thereof;

FIG. 3 is a bottom view thereof;

FIG. 4 is a right-side view thereof;

FIG. 5 is a left-side view thereof;

FIG. 6 is a back view thereof; and,

FIG. 7 is a front view thereof.

The dashed broken lines in the figures depict portions of the keyboard that form no part of claimed design.

1 Claim, 5 Drawing Sheets(56)
